UNITED STATES PATENT OFFICE.

PIERRE ARMENGAUD, OF COURBEVOIE, FRANCE.

INSULATING HANDLE FOR SAUCEPANS OR OTHER KITCHEN UTENSILS.

Application filed February 3, 1921. Serial No. 442,144.

To all whom it may concern:

Be it known that I, PIERRE ARMENGAUD, a citizen of the Republic of France, residing à Courbevoie, Seine, France, 74 Rue du 22

5 Septembre, have invented a new and useful Insulating Handle for Saucepans or Other Kitchen Utensils, of which the following is a specification.

This invention relates to the securing of 10 metallic, ceramic or other insulating sleeves or sockets upon the handles, lids or the like of saucepans and other vessels.

In the arrangements hitherto employed, there is generally provided a shank of which 15 one or both extremities is or are screw-threaded, one being screwed upon the stub or lug to which the saucepan handle is attached and the other end receiving a nut consisting for example of the metal cap which 20 serves to fix the insulating socket.

These arrangements apart from the disadvantage that they require components of rather complicated shape and a considerable amount of fitting in erection, do not allow a 25 secure attachment of the insulator.

The method of connection utilized in the present invention is free from all these disadvantages, and is characterized by the fact that a member placed on the end of the 30 shank of the saucepan handle and designed to retain the insulating socket in position, or the socket itself, is provided with a hole which is brought into register with that of the shank of the saucepan handle, the parts 35 being secured together either by hammering down the edges of the hole in the socket or in the independent member, inside the hole in the shank, or by the introduction of a ring slipped into the holes in the shank and 40 socket or retaining member when these have been brought into register, the said ring being fixed either by screwing or by turning over or expanding its ends.

The accompanying drawing represents by 45 way of example different forms of construction of saucepan handles with insulating sockets secured by the method of the present invention.

Figure 1 is a vertical longitudinal section 50 of a first form of construction, before fixing.

Figure 2 is a section on line 2—2 of Figure 1, after fixing.

Figure 3 is a vertical longitudinal section 55 of a second form of construction.

Figure 4 is a horizontal section on line 4—4 of Figure 3.

Figure 5 is a vertical longitudinal section of a third form of construction.

Figure 6 is a vertical longitudinal section 60 of a fourth form of construction.

The shank *a* of the saucepan handle upon which is slipped the insulating socket *b* is provided at its free extremity with a hole *c*. The metal cap *d*, Figures 1 and 3 and 5, having an opening *d'*, has also a mortised recess in which the free end of the shank engages. When the openings *c* and *d'* have been brought into register (Fig. 1) the cap *d* is fixed by hammering or beading over the edges *d*² of the opening *d'* as shown in 70 Figure 2. By turning down the metal more forcibly at one end than at the other, the desired firmness can be obtained so as to obviate any looseness of the insulating socket. 75

According to the second form of construction (Figures 3 and 4), when the openings *c* and *d'* have been brought into register, there is introduced therein a ring *f* which is then expanded or pressed down at its two 80 extremities, whilst at the same time it can be drawn or distorted to effect the locking of the insulating socket.

In the case where the insulated sleeve or 85 socket is composed of a metal tube *g* (Figure 5), there is arranged at each end an insulating washer *h*; in this way the tube *g* can never become heated by conduction.

The invention may also be employed where 90 no separate cap is used; in this case the insulating socket *b* forms a complete sheath (Fig. 6) for the shank *a*, and when the opening in the shank and socket have been brought into 95 register as in the previous examples, the locking ring *f*, which may be provided with a back-plate *f'*, is introduced into place and fixed. By interposing an insulating washer *h'* between the ring *f* and the periphery of the opening in the shank, the last-mentioned may even be kept from contact with the ring 100 *f*, and the latter thus prevented from becoming heated.

It will be evident that the invention is not limited to the details of construction which 105 have been described. For example, this method of attachment may be applied to the handles or knobs of saucepans, lids, or vessels of any shape, in which the shank is of a metal other than the vessel or lid, whether attached thereto or enclosed in the metal in casting; there may also be utilized for the manufacture of the cap any suitable metal. 110

2
The interior of the recess in the cap may be fitted with an insulating lining so as to prevent it from becoming heated by conduction, or the cap may be formed of two hollow halves stamped out and then pressed together; lastly the locking ring of metal or other suitable material may be fixed in any appropriate manner, as for instance, by screwing, pressing or otherwise.

10 Having now particularly described and ascertained the nature of my said invention and in that manner the same is to be performed, I declare that what I claim is:

15 1. An insulating handle for saucepans or other kitchen utensils, comprising a metal shank having an opening near its free end, an insulating sleeve, and means engaging said opening for locking the insulating sleeve relatively to the metal shank.

20 2. An insulating handle for saucepans or other kitchen utensils, comprising a metal shank having an opening near its free end,

an insulating sleeve, a retaining metal member upon the free end of said shank, an opening in said retaining member, and a ring introduced into both openings brought into register and secured in place in said openings. 25

3. An insulating handle for saucepans or other kitchen utensils, comprising a metal shank having an opening near its free end, 30 a retaining metal member upon the free end of said shank, an opening in said retaining member, and a ring introduced into both openings brought into register and secured in place in said openings, by expanding its edges over the edges of said openings. 35

In testimony whereof I have signed my name to this specification.

PIERRE ARMENGAUD.
